UNITED STATES PATENT OFFICE.

JOHN VAN KOLKEN, OF GREAT FALLS, MONTANA.

SLIDING DOOR.

1,134,781.

Specification of Letters Patent. Patented Apr. 6, 1915.

Application filed June 10, 1914. Serial No. 844,278.

To all whom it may concern:

Be it known that I, JOHN VAN KOLKEN, a citizen of the United States, residing at Great Falls, in the county of Cascade and State of Montana, have invented new and useful Improvements in Sliding Doors, of which the following is a specification.

The primary purpose of this invention is the provision of novel means for automatically operating complementary doors for closing openings in dwellings, buildings or like structures having doorways fitted with laterally sliding doors.

The invention consists of means embodying elements for normally holding the doors closed, means for utilizing the weight of a person when approaching the door opening for sliding the doors outward to expose the doorway through which ingress or egress may be had and means for securing the doors at any stage of their movement, such door securing means being readily controllable by push buttons or like manually operable devices, whereby the doors may be released or secured by proper manipulation of the manually controllable devices.

The invention consists of the novel features, details of construction and combination of parts, which hereinafter will be more particularly set forth, illustrated and claimed.

In the drawings hereto attached:—Fig. 1 is an elevation of sliding doors and actuating means therefor embodying the invention, showing the relation of the parts when the doors are closed. Fig. 2 is a view similar to Fig. 1 showing the relation of the parts when the doors are open. Fig. 3 is a horizontal section on the line $x-x$ of Fig. 1. Fig. 4 is a vertical section on the line $y-y$ of Fig. 2, looking in the direction of the arrows. Fig. 5 is a detail view of the means for holding the doors in the required position.

Corresponding and like parts are referred to in the following description, and indicated in all the views of the drawings, by the same reference characters.

The sliding doors 1 may be mounted in any manner to move in opposition and are arranged to close a doorway between communicating rooms, hallways or like places in dwellings or analogous structures. Such sliding doors are usually arranged to move into pockets formed in hollow partitions so that when opened the doors are hidden from

view and do not interfere in any manner with the appearance or furnishings of a room, hallway or other place. In accordance with this invention spaces 2 are formed in the lower portions of the doors 1 intermediate of the sides thereof and receive sectors 3 or similar parts, such sectors being pivoted at their lower ends as indicated at 4 and their outer edges being grooved to receive flexible connections 5, such as cords, chains or straps. Each of such flexible connections is attached at one end to a sector 3, as indicated at 7, and has its opposite end fastened to a door as shown at 6. Upper and lower bell cranks 9 and 10 are located within each of the pockets in which the doors 1 slide and the horizontal arms of such bell cranks are connected by means of a rod or bar 11 which is provided at its lower end with a weight 12 which is representative of a suitable counterbalance for exerting a downward pull upon the connection 11 to hold the door projected across the door opening. A pivoted rod or bar 8 adjustably connects the upwardly extending arm of the bell crank 10 with the door. A rod or bar 13 is connected at one end to the door and at its opposite end to the upwardly extending arm of the bell crank 9. When the door 1 is slid open the weight or counterbalancing means 12 is moved upward and when the door is released the weight 12, or like part, exerting a downward pull upon the connection 11 serves to project the door across the doorway into closed position.

A pit 14 is arranged beneath the doorway and receives the connecting means 16 and 16^a between two platforms 15. The parts 16^a are plates, whereas the part 16 is a pintle rod which passes through matching knuckles formed along the lower edges of the plates 16^a. The ends of the pintle rod 16 project and are connected to links 17 which in turn are connected to arms 17^a attached to the sectors 3. The platforms 15 are depressible and extend an equal distance upon opposite sides of the doorway so that a person approaching from either direction and stepping upon a platform depresses the same with the result that the doors are slid into open position. It must be remembered that when the doors are open the counterbalancing means 12 are moved upward, hence when the platforms are relieved of the weight of the person after passing through the doorway the doors are automatically closed by

the action of the counter balancing means returning to normal position. Leaves 18 are hinged to the ends of the platforms 15 and move therewith and prevent the formation of dangerous places at the ends of the platforms which would be liable to result in a fatality.

It is desirable at times to hold the doors open against the closing tendency of the 10 counter balancing means 12, hence means have been devised for effecting such results and in the simplest form, such means embody a bar 19 which is secured to the lower portion of one of the doors, a dog 20 ar- 15 ranged to engage the bar 19 and operating means for such dog. The dog 20 may be conveniently mounted either upon the partition or floor and may be of any construction so long as it is adapted to engage the bar 19 20 and hold the doors at the required adapted position within their range of movement. A lever 21 mounted between its ends has the dog 20 connected thereto. A second lever 22 mounted between its ends and arranged 25 within convenient position has its extremities coupled to corresponding ends of the lever 21 by suitable connections 23. Push buttons 24 are connected with the lever 22. By properly manipulating the push buttons 30 24 the dog 20 may be moved into or out of engagement with the bar 19, thereby securing the doors or effecting a release thereof.

From the foregoing description, taken in connection with the accompanying drawings, the advantages of the construction and of the method of operation will be readily apparent to those skilled in the art to which the invention appertains, and while I have described the principle of operation of the 35 invention, together with the device which I now consider to be the best embodiment

thereof, I desire to have it understood that the device shown is merely illustrative, and that such changes may be made when desired as are within the scope of the invention as claimed.

Having thus described the invention, what is claimed as new is:-

1. In combination, a sliding door for controlling a doorway, platforms arranged upon opposite sides of the doorway, connecting means between the platforms and door and leaves hinged to the ends of the platforms and extending outward therefrom.

2. In combination, sliding doors having recesses, platforms arranged upon opposite sides of the doors, a pintle rod connecting the platforms, pivoted sectors operating in the recesses and having flexible connection with the doors, and connecting means between the ends of the pintle rod and the sectors.

3. In combination, sliding doors having recesses, platforms arranged upon opposite sides of the doors, sectors operating in the recesses, connecting means between the sectors and platforms, and flexible connecting means between the sectors and doors.

4. In combination, a sliding door having a recess in its lower portion, a depressible platform, a pivoted operating member arranged within the recess of the door, connecting means between such operating member and platform, and a flexible connection between the operating member and sliding door.

In testimony whereof I affix my signature in presence of two witnesses.

JOHN VAN KOLKEN.
